UNITED STATES PATENT OFFICE.

JOSEPH R. FRANCE, OF NEW YORK, N. Y., ASSIGNOR TO THE METALLIC CAP MANUFACTURING COMPANY, OF SAME PLACE.

BLASTING-CAP.

SPECIFICATION forming part of Letters Patent No. 356,712, dated January 25, 1887.

Application filed November 2, 1886. Serial No. 217,834. (No model.)

To all whom it may concern:

Be it known that I, JOSEPH R. FRANCE, a citizen of the United States, residing at New York, in the county of New York, and State 5 of New York, have invented new and useful Improvements in Blasting-Caps, of which the following is a specification.

My invention relates to certain improvements in blasting-caps or exploders for exploding nitro-glycerine, dynamite, gelatine-powder, or other explosive material. It is the object of my invention to render such detonators instantaneous in action throughout the cartridge to be exploded, thereby increasing 15 the force and obtaining results which are better and greater.

It is also my purpose to provide a construction by which there shall be free egress to the burning gas or spark to the mixture to be detonated and to increase the ignition surface, whereby the burning gas from the fuse, or the spark, if electricity is used, reaches a considerable surface at one and the same instant.

My invention consists in the several novel 25 features of construction and combinations of parts hereinafter fully set forth, and definitely pointed out in the claims following this specification.

In the accompanying drawings, Figure 1 is 30 a detail view of a fulminate-cap constructed according to my invention. Fig. 2 is a sectional view of the same incased in a copper shell.

Heretofore and prior to my invention caps 35 for blasting purposes have usually been made by partly filling a copper shell with fulminate of mercury, or a compound of such fulminate with chlorate of potash, gun-cotton, or other substances, said compound being forced into or 40 compressed by a plunger within the metallic shell, usually filling it about one-quarter full. These caps or detonators are usually ignited or fired by a fuse, though an electric spark is sometimes used, and although they are apparently instantaneous in action they are, in 45 fact, not so, since the first grains or atoms of fulminate receive the burning gas (or the spark, if electricity is used) and in turn communicate the shock to the next grains, and so on 50 until its inertia is extended throughout the cartridge to be exploded. The more nearly instantaneous or simultaneous this explosion can be made the better and greater are the re-

sults obtained from the powder, dynamite, or other compound exploded by the detonator.

In the drawings referred to the reference-numeral 1 designates a cap or detonator formed of any suitable substance—such as fulminate of mercury, or fulminate mingled with chlorate of potash or other compound, such as a high grade of gun-cotton—the substances employed being mingled in suitable proportions. A quantity of the compound is then compressed into the shells in the ordinary plunger-presses, the plungers being provided 65 with a point by which a conical chamber or recess, 2, is centrally formed in the mixture extending to or nearly to the bottom of the shell or cap 1.

The manner of forming these caps is as follows: The material composing the cap is placed in a copper shell, 3, of suitable caliber, and is then acted upon by a plunger operated by a suitable press. The plunger is of such form as to produce the conical opening of a 75 suitable depth, and at the same time compress the explosive of which the cap is formed, the latter usually occupying about one-fourth the depth of the shell 3.

The opening or chamber 2 is of conical 80 form, preferably, but may be made of other forms, if desired. So, also, the opening may penetrate to or nearly to the lower end of the fulminate-cap, or be of any suitable depth, without departing from my invention.

Having thus described my invention, what I claim is—

1. A blasting-cap or detonator consisting of a compressed body of fulminating material or compound, having an open chamber extending 90 from one end toward its other end, in combination with a shell partly filled only by said compressed body of fulminating material or compound, substantially as described.

2. A blasting-cap or detonator composed of 95 a fulminating material or compound, and provided with a conical chamber or recess extending to or toward the bottom, in combination with a copper shell, which is partly filled by the cap, substantially as described.

In testimony whereof I affix my signature in presence of two witnesses.

JOSEPH R. FRANCE.
